UNITED STATES PATENT OFFICE.

GIORDANO ZILOCCKI, OF NEW YORK, N. Y., ASSIGNOR OF ONE-HALF TO OSWALD SCANLON, OF JERSEY CITY, NEW JERSEY.

SPIRAL-SPRING-WINDING DEVICE.

1,413,150.

Specification of Letters Patent. Patented Apr. 18, 1922.

Application filed December 7, 1920. Serial No. 429,029.

To all whom it may concern:

Be it known that I, GIORDANO ZILOCCKI, a citizen of Italy, and residing at New York, in the county of New York and State of 5 New York, have invented certain new and useful Improvements in Spiral-Spring-Winding Devices, of which the following is a specification, such as will enable those skilled in the art to which it appertains to 10 make and use the same.

This invention relates to tools for use in winding wire on a mandrel to form wire coils and particularly to what are known as spring coils, and the object of the invention 15 is to provide a tool of the class specified which is so constructed as to permit of the winding of wire coils of varying dimensions within certain limits; a further object being to provide adjustable means for gaging 20 the space between the separate coils of the wire in the operation of forming a spring or wire coil; and with these and other objects in view the invention consists in a tool of the class and for the purpose specified 25 which is simple in construction and operation and efficient in use, and which is constructed and operated as hereinafter described and claimed.

The invention is fully disclosed in the following specification, of which the accompanying drawing forms a part, in which the 30 separate parts of my improvement are designated by suitable reference characters in each of the views, and in which:—

35 Fig. 1 is a plan view of my improved tool and diagrammatically illustrating the method of its use;

Fig. 2 a partial section on the line 2—2 of Fig. 1;

40 Fig. 3 a detail view showing a part of the gage device of my improved tool and the method of its use;

Fig. 4 a view similar to Fig. 3 but showing the gage in a different position; and,

45 Fig. 5 a bottom plan view of the gage device shown in detail in Figs. 3 and 4.

For the purpose of illustrating the use of my invention, I have indicated at 10 in the accompanying drawing a mandrel which is 50 adapted to be rotated by a suitable machine, such for example, as a lathe, and to one end portion of which is secured a collar 11. My improved tool 12 is adapted for use in connection with the mandrel 10 and comprises 55 an approximately T-shaped body portion 13

with which a handle member 14 is connected, and the cross head 15 of the body portion 13 is provided with an aperture 16 adapted to receive a cylindrical bushing 17 held in place by a set screw 18.

The bushing 17, or the aperture 19 thereof, is slightly greater in diameter than the diameter of the mandrel 10 employed, the extent of this difference being determined by the diameter of the wire 20 employed.

The cross head 15 is provided with an aperture 21 and the bushing 17 with a corresponding aperture 22 to permit of the passage of the wire 20 into the aperture 19 and around the mandrel 10, as hereinafter set 70 out. The body portion 13 is enlarged centrally as indicated at 23, and a sleeve 24 is adjustably mounted therein and held in different positions of adjustment by a lock member 25, and a gage device 26, in the 75 form of a screw, is adjustably mounted in the sleeve 24 and held in different positions of adjustment by a lock member 27. The inner face of the gage device is provided with a comparatively thin transverse projection 28 which is adapted to cooperate with the periphery of the mandrel 10, as herein-after set out. The lock members 25 and 27 are each provided with radially extending arms 29 and 30 respectively, as illustrated 80 in Fig. 1 of the drawing whereby said members may be quickly and conveniently manipulated whenever desired.

By reason of the adjustable sleeve 24 the gage device 26 may be moved radially of the 90 body portion 13 without rotating the same in this operation, and this will be necessary in order to permit of the winding of a single coil, the separate coils of which, or the distance therebetween will vary, in other words, 95 a single coil may be produced with both closely arranged and widely spaced coils therein.

The use of my improved tool will be 100 readily understood from the foregoing description when taken in connection with the accompanying drawing and the following statement. After the tool 12 has been mounted on the mandrel 10 and the mandrel placed in a suitable machine, the free end 105 of the wire 20 is passed inwardly through the apertures 21—22 around the transverse projection 28 and laterally through the aperture 19 of the bushing 17 and is secured to the collar 11, as shown at 31 in Fig. 1 of 110

the drawing, the tool 12 being in juxtaposition to said collar in this operation. The mandrel 10 is then rotated by the machine in which it is mounted and the wire 20 will 5 be wound upon said mandrel to form a spiral coil 32, and the operation of winding the wire 20 upon the mandrel 10 will automatically feed the tool longitudinally of said mandrel. The distance between the separate 10 rate coils of the spring is regulated by a gage device 26, or the relative position of the transverse projection 28 thereof to the longitudinal line of the mandrel, and by means of the adjustable or radially movable gage 15 device, I may wind upon the mandrel 10 in one operation a coil or wire, the distance between the separate coils or windings of which may be of the same dimensions throughout, or may vary, if desired, in other 20 words, a part of the coil may be wound as shown in Fig. 3 of the drawing and another part as shown in Fig. 4 of the drawing, or a complete coil may be wound as shown in Fig. 3 or Fig. 4, it being understood that 25 differently spaced coils than those shown in said figures may also be wound on the mandrel by reason of the adjustment of the gage device 26.

It will also be apparent that the bushing 30 17 shown in the accompanying drawing may be removed, whenever desired, and another bushing employed having apertures 19 of different dimensions, in which event the diameter of the mandrel employed will also 35 be varied to correspond with the sides of the aperture in the bushing employed, as well as the size or gage of the wire employed, and while I have shown certain details of construction for carrying my invention into 40 effect, it will be understood that various changes therein and modifications thereof may be made, within the scope of the appended claims, without departing from the spirit of my invention or sacrificing its 45 advantages.

Having fully described my invention, what I claim as new and desire to secure by Letters Patent, is:—

1. A tool of the class described comprising 50 a body portion, a bushing mounted in the body portion and provided with an aperture, means whereby a wire may be passed through said body portion into the aperture of said bushing, and a gage device adjustably mounted in the body portion and extending into the aperture of said bushing and in connection with which the wire operates.

2. A tool of the class described adapted 60 for use upon a suitable mandrel and comprising a suitable body portion, a bushing detachably mounted in the body portion and through which said mandrel is adapted to pass, means whereby a wire may be passed 65 through said body portion and into said

bushing to permit of the winding thereof on said mandrel, and adjustable means in the body portion cooperating with said wire to regulate the winding of said wire on said mandrel. 70

3. A tool of the class described adapted for use upon a suitable mandrel and comprising a suitable body portion, a bushing detachably mounted in the body portion and through which said mandrel is adapted to 75 pass, means whereby a wire may be passed through said body portion and into said bushing to permit of the winding thereof on said mandrel, adjustable means in the body portion cooperating with said wire to 80 regulate the winding of said wire on said mandrel, and means for locking said last named means in different positions of adjustment.

4. A tool of the class described adapted 85 for use upon a suitable mandrel and comprising a suitable body portion, a bushing detachably mounted in the body portion and through which said mandrel is adapted to pass, means whereby a wire may be passed 90 through said body portion and into said bushing to permit of the winding thereof on said mandrel, adjustable means in the body portion cooperating with said wire to regulate the winding of said wire on said 95 mandrel, and means for withdrawing said last named means.

5. A tool of the class described adapted for use upon a suitable mandrel and comprising a suitable body portion, a bushing 100 detachably mounted in the body portion and through which said mandrel is adapted to pass, said body portion and said bushing being apertured to permit of the passage of a wire into the aperture of said bushing to 105 permit of the winding thereof on said mandrel, and a gage device mounted in the body portion and cooperating with said mandrel to regulate the winding of said wire on said 110 mandrel.

6. A tool of the class described adapted for use upon a suitable mandrel and comprising a suitable body portion, a bushing detachably mounted in the body portion and through which said mandrel is adapted to 115 pass, said body portion and said bushing being apertured to permit of the passage of a wire into the aperture of said bushing to permit of the winding thereof on said mandrel, a gage device mounted in the body 120 portion and cooperating with said mandrel to regulate the winding of said wire on said mandrel, said gage device being adjustable, and means for moving said gage device toward and from said mandrel in any position of adjustment.

7. A tool of the class described adapted for use upon a suitable mandrel and comprising a suitable body portion, a bushing detachably mounted in the body portion and 130

through which said mandrel is adapted to pass, said body portion and said bushing being apertured to permit of the passage of a wire into the aperture of said bushing 5 to permit of the winding thereof on said mandrel, a gage device mounted in the body portion and cooperating with said mandrel to regulate the winding of said wire on said mandrel, said gage device being adjustable, 10 means for moving said gage device toward and from said mandrel in any position of

adjustment, and means for locking said gage device in different positions of adjustment.

In testimony that I claim the foregoing as my invention I have signed my name in 15 presence of the subscribing witnesses this 4th day of December, 1920.

GIORDANO ZILOCCKI.
